UNITED STATES PATENT OFFICE.

FRANK BURKETT, OF LUFKIN, TEXAS.

BOILER-TUBE.

1,146,050.

Specification of Letters Patent. Patented July 13, 1915.

Application filed September 17, 1912. Serial No. 720,861.

To all whom it may concern:

Be it known that I, FRANK BURKETT, a citizen of the United States, residing at Lufkin, in the county of Angelina and State 5 of Texas, have invented a new and useful Boiler-Tube, of which the following is a specification.

The present invention relates to improvements in boiler tubes, the primary object of 10 this invention being the provision of a non-corrodible sheet engaging end for the tube, the same being so constructed and arranged as to be readily sweated or brazed to the usual steel or iron boiler tube, such construction reducing the cost of installation and removal and at the same time a more durable 15 securing means between the tube and sheet.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed can be made within the scope of what is claimed without departing from the spirit of the invention.

In the drawings—Figure 1 is a sectional view through a boiler sheet with one of the 30 boiler tubes attached thereto. Fig. 2 is a longitudinal sectional view through the boiler tube adjacent to the non-corrodible end thereof.

Referring to the drawings, the numeral 35 1 designates the boiler sheet and 2 the tube. The steel section 3 of the tube is slightly tapered as at 4 for the reception of the inner tapered end 6 of the non-corrodible sheet 40 engaging tube or end 7, which is preferably made of copper or a malleable non-corrodible metal having the same qualities as copper. The meeting ends of the section 3 and end 7 are brazed by suitable brazing metal 5 and thus a homogeneous junction is produced be-

tween the copper and steel, as clearly shown 45 in Fig. 2. As shown in Fig. 1, the extreme outer end of the non-corrodible section 7 is expanded as at 8 and thus provides a water tight joint between the tube and sheet, and a means whereby the tubes may be readily 50 removed and replaced when necessary.

By constructing the ends of boiler tubes as herein set forth, a strong tube is produced, and as the connection with the boiler sheet is made by expanding the malleable 55 non-corrodible connecting end therewith, it is evident that the cost of installation as well and the initial cost of the tube is reduced.

With the present boiler tube, the sudden contraction and expansion that often cracks 60 and breaks steel and iron tubes, does not have this bad effect, and thus this tube is more durable and inexpensive in use.

What is claimed is:

A boiler tube, including a main section 65 having its end tapered exteriorly to a relatively thin rim, a non-corrodible boiler sheet engaging nipple, one end of which is of a reduced diameter, but the thickness of the walls of which are the same throughout, a 70 portion of said end being inserted within and out of contact with the mouth of the main section, and a uniting brazing metal filling the circumferential space between the telescopic portion of the main section and 75 the nipple and surrounding the nipple as a continuation of the tapered relatively thin rim of the main section, whereby a reinforced and water tight joint is provided both by the incased end of the nipple and the 80 uniting metal about the nipple.

In testimony that I claim the foregoing as my own, I have hereto affixed my signature in the presence of two witnesses.

FRANK BURKETT.
